CAPSULE FILLING DEVICE

Mathew Kastrin and George Makres, Detroit,
Mich., assignors, by direct and mesne assignments,
of one-half to said Kastrin and one-half to Sam Karos, Detroit, Mich.

Application March 2, 1951, Serial No. 213,518

7 Claims. (Cl. 226—41)

1

This invention relates to a capsule filling device and more particularly to an improved device for filling or loading capsules of the split, hard shelled type.

An important object of this invention is to provide a capsule filling device particularly adapted for use by druggists and pharmacists for filling or loading capsules of the split, hard shelled type and which is constructed in an improved manner for simultaneously filling a plurality of capsules, for applying the cap portions thereto, and for ejecting the filled, closed capsules from the device. Another important object of the invention is to provide an improved device of this character including a movable member or plate yieldingly urged in one direction and novel conveniently operable means for releasably locking or holding the plate in different positions for filling and capping the capsules. A further important object of the invention is to provide a device of this character which is designed for economical manufacture and for efficient and accurate use and which is substantially wholly composed of rigid plastic material.

In carrying out the objects of the invention, the device preferably comprises three plate members, two of which are stationary and supported in vertical spaced apart relationship to one another and the remaining one of which is guided for up and down movement relative to the two stationary members. Preferably the top member is a perforated stationary plate and the movable member an imperforate plate guided for up and down travel between the top and bottom plates. The movable plate is yieldingly forced upwardly toward the top plate and at intermediate positions it serves as a rest for the bottoms of the capsules while they are filled and capped and in its final upward movement it lifts the capsules through the perforated top plate for removal from the device. Incorporated in the device and preferably associated with handles on the movable middle plate is a releasable catch or locking mechanism for releasably holding the middle plate at one position for filling the main body portions of the capsule and at another position for applying the caps to the main body portions of the capsules. The final upward movement from the second position is utilized to eject the filled and closed capsules from the apertures in the top plate.

Various other objects, advantages and meritorious features of the invention will become more fully apparent from the following specification, appended claims and accompanying drawings, wherein:

2

Fig. 1 is a top plan view of an embodiment of the invention showing the top plate thereof being provided with a plurality of apertures of different sizes in which the capsules are received,

5 Fig. 2 is a vertical sectional view through the center line of the device of Fig. 1,

Fig. 3 is a fragmentary sectional view of the device taken along line 3—3 of Fig. 1,

10 Fig. 4 is an enlarged horizontal fragmentary sectional view taken along line 4—4 of Fig. 2,

Fig. 5 is a vertical longitudinal sectional view similar to Fig. 2 but on a smaller scale and illustrating a modified form of the invention in the capsule filling position,

15 Fig. 6 is a sectional view similar to Fig. 5 but showing the device in capsule capping position,

Fig. 7 is a sectional view similar to Figs. 5 and 6 but showing the device in capsule ejecting position,

20 Fig. 8 is an enlarged vertical sectional view taken along line 8—8 of Fig. 7,

Fig. 9 is an enlarged fragmentary vertical sectional view taken along line 9—9 of Fig. 7,

25 Fig. 10 is an enlarged perspective view of the control member and associated parts of the modification, and

Fig. 11 is a vertical sectional view of the top portion of a further modified form of the invention.

In the various embodiments of the invention 30 illustrated in the drawings, the capsule filling, capping and ejecting device comprises three members or plates, two of which are held stationary with respect to one another and are vertically spaced apart from one another. Movable

35 with respect to these two plates and preferably positioned therebetween is a third member or plate which serves as a rest for the bottoms of the main body portions of the capsules. The third plate is yieldingly urged upwardly toward the top plate. In one position of the middle plate, it predisposes the main body portion of the capsule for filling the same. In another position at a higher level than the first position, the middle plate supports the main body

40 portion of the capsules in projecting relation to the top plate for receiving the cap portions. Releasable catch means is provided, and preferably carried by the middle plate, for holding the middle plate at either of the two positions and

45 against the force of the yielding means urging the middle plate upward. Preferably, the locking means is associated with handles for depressing the middle plate in order that the operator may conveniently control the movement of the

50 middle plate.

Referring to the embodiment of the invention illustrated in Figs. 1 to 4, the bottom or base plate is indicated at 10. The top plate is indicated at 12, and as shown in Fig. 1 is provided with a plurality of apertures therethrough in which capsules are positioned during the filling and capping operations. Preferably the top plate is provided with one or more different sizes of apertures for capsules of various sizes, one such size of aperture being indicated at 14 and another size of aperture at 16. The plates 10 and 12 are disposed in vertical spaced apart relationship and are combined into a unitary assembly by means of corner posts indicated at 18. In the embodiment illustrated in Figs. 1 to 4, the corner posts are channel shaped in formation and open inwardly of the device. Each channel shaped post comprises a member 20 forming the base of the channel and extending flush with one side of the device and two spaced apart side wall members 22-22 cooperating with the base to form the channel. Preferably the bottom plate 10, top plate 12 and the corner posts 18 are formed of plastic material.

Positioned between the bottom and top plates 10 and 12 is a third member or plate 24, preferably also composed of plastic material. This third plate is movable with respect to the stationary plates 10 and 12 and is yieldingly constrained in an upward direction toward the top plate 12. For this purpose, there is provided in each channel shaped corner post 18 a shaft or rod 26 which is encircled by a coiled spring 28. The middle plate is provided with laterally extending tongues or ears at each corner, such as indicated at 30, which enter the channel shaped posts 18. Each ear is provided with an aperture 32 aligning with the rod 26 in the corner post into which it extends. By virtue of this construction, it is evident that the middle plate 24 may be slidably depressed down the rods 26 while the ears 30 thereof are guided in the channel shaped posts. Such downward movement is resisted by the coiled springs 28, the upper ends of which are seated against the ears 30. The coiled springs are of such a strength that when any downward pressure on the plate 24 is relieved, they will raise the middle plate 24 to its highest level, such as that shown in Fig. 3. One or more spacers indicated at 34 may be provided for limiting the upward movement of the middle plate 24. These spacers or stops may be secured to the corners of the top plate 12 as shown in Fig. 3 and depend downwardly therefrom into the channel shaped corner posts 18.

Carried by the middle plate and projecting upwardly therefrom are a plurality of pins 36, one of which is shown in detail in Fig. 3. The bottom ends of the pins are secured to the middle plate for joint movement therewith. The upper ends of the pins, as shown in Fig. 3, may be concavely indented as indicated at 38 to form a radius of curvature corresponding to the bottoms of the main body portions of the capsules. The pins 36 are mounted on the middle plate 24 in axial alignment with the apertures 14 and 16 of the top plate and are of such a length that when the middle plate is raised they enter the apertures and at the maximum level height of the middle plate extend flush with the upper surface of the top plate, as indicated in Fig. 3.

As heretofore mentioned, control means is provided for releasably holding the middle plate 24 at two different levels in its vertical path of travel. For this purpose the middle plate 24 is

provided with two laterally extending handle portions 40-40 projecting from opposite sides thereof as is evident in Figs. 1 and 2. These handle portions may be engaged by the hands of the operator and employed to depress the plate 24 against the resistance of the springs 28. Preferably carried by at least one of the handles 40 is an actuating member or lever for releasably locking the plate. In the two positions previously mentioned it is preferred to mount the actuating mechanism on one of the handles 40 in order that the operator may control the movement of the middle plate while his hands are engaging the handles.

The releasable holding means for the middle plate 24 comprises two vertical extending rods or posts 42-42 of similar construction to one another. Each post is provided with two sections of reduced thicknesses to form shoulders with which the movable part of the holding mechanism is engageable. As shown in Fig. 2, each rod or post 42 is cylindrical in formation and is provided intermediate its ends with one reduced section indicated at 44 and another reduced section indicated at 46. These two reduced sections of each post 42 may be cylindrical in formation as shown and of progressively less diameter as the bottom of the device is approached. The reduced section 44 of each post 42 forms with the normal diameter thereof a shoulder 48. Similarly, the smallest reduced section 46 of each post forms with the section 44 a shoulder 50. Releasable catch or latching means hereinafter described is provided with middle plate 24 for engaging the shoulders 48 and 50 of the posts 42-42.

Although each handle 40 may be provided with releasable latching means for engaging the shoulders of the adjacent post 42, the embodiment of the invention illustrated in Figs. 1 to 4 uses only one latching mechanism and employs remote control means for engaging the shoulders of the post 42 on the opposite side of the device.

Referring to Figs. 1 and 2, an elongated control member, preferably of plastic material, is indicated at 52 and extends from one post 42 to the other post 42. The member 52 is provided with an extension 54 which overlies one of the handles 40 of the middle plate, such as the handle shown at the right of Figs. 1 and 2. The control member 52 is widened immediately adjacent to the posts 42-42 in the manner best indicated at 56 in Fig. 4. Positioned in each widened portion 56 of the control member 52 is a slot of the character indicated at 58. Each slot 58 is elongated in the longitudinal dimension of the control member 52 and its width is progressively decreased from one end to the other end thereof. As best shown in Fig. 4, the slot 58 is provided with circular sections progressively decreasing in diameter from one end to the other end thereof. The largest diameter circular portion of the slot is indicated at 60 and is of a size to permit the widest part of the post 42 associated therewith to project therethrough. The next widest portion of the slot is indicated at 64 and its diameter is such that it will ride over the reduced section 44 of the post and abut the shoulder 48 thereof. The smallest diameter of the section of the slot is indicated at 66 and is of such a size to slide up and down the narrowest reduced section 46 of the post and abut the shoulder 50 thereof.

It is evident from the description thus far made that when the control member 52 is moved

longitudinally toward the left in Fig. 2 it will progressively bring larger diameter sections of the slots 58—58 into encircling relationship to the axes of the posts 42—42. When the middle plate 24 is fully depressed the narrowest section 66 of each slot 58 is capable of being brought in under the shoulders 50 of the posts 42—42 and the resulting abutting engagement therewith will releasably hold the plate in its fully depressed position. However, if the control member is moved toward the left in Fig. 2 it will bring the intermediate sections 64 thereof into alignment with the axes of the posts 42—42 permitting the springs 28 to lift the plate until the portions of the control member forming the intermediate sections 64 of the slot abut the shoulders 48 of the posts 42—42. In this position, the control member will releasably hold the plate 24 at an intermediate level above the full line position shown in Fig. 2. When the control member is shifted further to the left in Fig. 2, it will bring the largest sections 60 of slots 58—58 into axial alignment with the posts 42—42 permitting the springs 28 to lift the middle plate until they abut the stopping members 34. The highest level position of the plate 24 is indicated in dotted outline in Fig. 2 and in fully outlined position in Fig. 3.

Hand operated means is provided for reciprocating the control member 52 and preferably such means is mounted on and associated with one of the projecting handles 40 of the middle plate 24. As shown in Figs. 1 and 2, the right hand handle 40 is provided with two upstanding spaced apart bracket members 68—68 which are spaced apart from one another and are connected together by means of a cross pin 70. Pivotedly connected to the cross pin is a lever 72 which is adapted to be engaged by the hand of the operator. Extending downwardly from the pivotally connected end of the lever 72 and at substantially right angles thereto is an arm 74 which is operatively connected to the extension 54 of the control member 52. For this purpose, the extension 54 is provided with two upstanding longitudinally spaced apart elements 76—76 which together form a notch for receiving the arm 74, as is clearly evident in Fig. 2. The relationship of the handle 72 to the extension 54 is such that when the handle 72 is swung downwardly about its pivotal axis the arm 74 will advance the control member 52 toward the left bringing successively larger sections of the slots 58 into axial alignment with the posts 42—42. The compressible movement of the lever 72 is yieldingly opposed by means of a spring which may be in the form of a flexible metallic member 78 secured at its opposite ends to the lever and to the handle 40 and looped one or more times between its ends, as shown in Fig. 2. The spring 78 functions to yieldingly retract the control member 52 to the right whenever pressure on the lever is relieved.

In the lowermost position of the movable plate 24, which is shown in full line in Fig. 2, the upper ends of the pins 36 carried thereby are disposed below the plate 12 and at such a level that the main body portions of the capsules may be fully received in the apertures 14 and 16. As shown in Fig. 2, the body portion of a larger type of capsule is indicated at 80. The body portion of a smaller type of capsule is indicated at 82. The body portions 80 and 82 of the capsules are inserted into the apertures of the top plate 12 when the middle plate 24 is in its fully depressed position and the base ends of the capsule body portions are seated on the indentations 38 of

the pins and supported thereby. So supported, the upper ends of the body portions 80 and 82 of the capsules extend substantially flush with or slightly below the upper surface of the top plate 12 and are in a position to receive content material either in dry or liquid form.

After the body portions 80 and 82 of the capsules are filled with content material to the desired amount, the operator depresses the lever 72 sufficiently to bring the intermediate sections 62 of the slots 58 into axial alignment with the posts 42—42. This will clear the control member from the lower shoulders 50 of the posts and permit the spring to raise the plate 24 until the shoulders 48 of the posts are engaged by the control member. During the rising of the plate 24 to the second high level position, the pins 36 project the upper ends of the main body portions of the capsules above the upper surface of the plate 12, the extent of this projection being such that the cap portions of the capsules may be fitted over the body portions. The resulting position of the capsules is shown in dotted outline in Fig. 2. In this projected condition, a cap portion 86 is telescopingly receivable over the larger capsule body portion 80, and the smaller cap portion 88 is slidably fitted over the smaller capsule body portion 82.

To eject the capsules from the device, the operator further depresses the lever 72 bringing the largest diameter sections 60 of the slots 58 into axial alignment with the posts 42—42. This will release the plate 24 for pivotal upward movement by the spring 28 and cause the upper ends 35 of the pins 36 to reach a level approximating that of the upper surface of the top plate 12. The result is that the filled and sealed capsules are ejected from the apertures and fall over on their sides on the upper surface of the top plate 40 in the manner shown in Fig. 3. These ejected capsules may be easily picked from or swept off of the upper surface of the top plate 12.

It is noted that the pins 36 project varying distances above the middle plate 24 depending upon the size of the capsule engaging plate. For example, the pins at the right of Fig. 2 project to a higher level than the pins at the left in order to fully eject the smaller type of capsules from the apertures of the top plate 12.

In the modification of the invention illustrated in Figs. 5 to 10 inclusive, the middle plate is capable of ejecting the capsules without the need of projecting pins of the character shown at 36 in the earlier described embodiment of the invention. In general, the modification follows the previously described embodiment and includes a base or bottom member 90, a spaced top member 92, and a movable middle plate 94. The middle plate is provided with laterally extending handle portions, one of which is indicated at 96 at the left of Figs. 5 to 7 and the other of which is indicated at 98 at the right thereof. The top and bottom plates 90 and 92 are spaced apart in the same manner as previously described by corner posts indicated at 100. The middle plate is guided for up and down movement by these corner posts and it is releasably held at filling and capping positions in the manner generally like that previously described. As shown in Figs. 5 to 8, two opposite sides of the device are provided with posts 102—102 corresponding with posts 42—42 previously described. Each post 102 is shaped to provide shoulders around its length for engagement by releasable catch means carried by

the middle plate. Each post 102 may, for example, be reduced cross sectionally intermediate its ends to form a shoulder 104 corresponding in function to shoulder 48 and a second shoulder 106 corresponding in function to shoulder 50.

The middle plate 94 is preferably jogged transversely across the mid section thereof to dispose one half section thereof at a higher level than the other half section. The jog between the two half sections is indicated at 108 and by such a provision the device is capable of receiving and filling capsules of two different sizes. The body portion of a smaller type of capsule is indicated at 110, and the body portion of a larger type of capsule is indicated at 112.

Extending longitudinally across the middle plate 94 and operatively engageable with the shoulders 104 and 106 is a control member 114 similar in construction and function to the control member 52 previously described. One end of the control member 114 overlies a handle 98, such as the handle at the right of Figs. 5, 6 and 7. Supported upon the handle over which the control member 114 lies is a manually operable arm or lever 116 constructed similarly to the lever 72 and including a depending detent or dog 118 which is engageable in a recess formed in the extremity of the control member 114. The lever 116 is pivoted at 120 and is yieldingly urged in an upward direction by means of a spring member 122 similar to the spring 78 previously described. For that portion of the length of the control member 114 which overlies the lower half section of the middle plate 94, there is preferably provided a supporting ridge 124 which underlies the control member and supports it in an elevated position upon the depressed section of the middle plate. For the remaining half section of the middle plate, the control member 114 may be positioned in a recess so that its upper face extends flush with the upper face of the plate as indicated in dotted outline in Figs. 5, 6 and 7. To guide the longitudinal slideable movement of the control member 114 and to limit its movement, the control member may be provided with one or more longitudinal slots 126 through which a screw 128 extends, as shown in Figs. 9 and 10.

What we claim is:

1. In a capsule filling machine, a bottom plate, a top plate, corner posts supporting the top plate in spaced parallel relationship to the bottom plate, said top plate provided with apertures for receiving the cup members of split type capsules, a middle plate disposed between the top and bottom plates, means guiding said middle plate for up and down movement relative to the top and bottom plates, means yieldingly urging the middle plate upwardly toward the top plate, a handle projecting laterally from one side of the middle plate, and releasable catch means for releasably locking the middle plate in spaced relationship below the top plate counter the means yieldingly urging the same toward the top plate, said catch means including a part carried by the handle.

2. A capsule filling machine comprising, in combination, three parallel plates vertically disposed with respect to one another, corner posts connecting the top and bottom plates together into a unitary structure, said top plate being provided with a plurality of apertures of a size to admit the cup members of split type capsules, said middle plate constituting a rest for the bottom of the cup members received in the apertures of the top plate, spring means encircling the cor-

ner posts and yieldingly urging the middle plate toward the top plate, a handle projecting from one side of said middle plate, means for releasably locking the middle plate in spaced relationship below the top plate including a manually operable lever carried by said handle.

3. In a capsule filling apparatus, the combination of a perforated plate having apertures adapted to receive the capsule members, an imperforate plate capable of being moved in perpendicular relationship to the plane of the first mentioned plate and theretoward to force the capsule members out of the apertures of the perforated plate, spring means yieldingly urging the imperforate plate toward the perforate plate, a stationary post extending through the imperforate plate, said post having shoulders spaced longitudinally therealong, and releasable catch means carried by the imperforate plate adapted to engage the shoulders of the post to releasably hold the imperforate plate from movement toward the perforate plate.

4. In a capsule filling machine, the combination of means for handling the cup members of split type capsules comprising two plates, one of which is perforated and the other of which is imperforate, said plates being disposed in parallel relation to one another so as to form a supporting seat for the cup members inserted through the perforations of the perforated plate, means yieldingly urging the imperforate plate toward the perforated plate, a stationary post extending through the imperforate plate and provided with shoulders therealong, and releasable catch means carried by the imperforate plate and operable to engage the shoulders of the post to releasably hold the imperforate plate against movement.

5. In a capsule filling device, the combination of a base plate, a capsule holding plate mounted in spaced relation from the base plate and provided with a plurality of apertures for receiving the cup members of split type capsules, corner posts extending between said base plate and said apertured plate connecting the same into a unitary assembly, a middle plate positioned between the base and the top plates and guided for movement on said posts, coil springs encircling said posts and urging the middle plate upwardly toward the top plate, a plurality of upright pins carried by the middle plate and axially aligning with the apertures in the top plate and adapted upon upward movement of the middle plate to eject capsules received in the apertures of the top plate, a pair of handles projecting laterally from the opposite sides of the middle plate, and means for releasably holding the middle plate in spaced relationship to the top plate including a hand actuatable lever carried by one of said handles.

6. In a capsule filling apparatus, a base plate, a perforated capsule filling plate disposed over said base plate, corner posts connecting the two plates together into a unitary assembly and such that the perforated plate is disposed in spaced relationship to the base plate, a member disposed between said two plates and guided for up and down movement relative thereto, said member adapted to form a rest for the bottom ends of capsules inserted through the perforations of said perforated plate, coil springs encircling said corner posts and yieldingly urging the member upwardly toward the perforated plate, a pair of handles carried by the member and projecting laterally from opposite sides thereof for depress-

ing said member against the tension of said springs, and means for releasably holding the middle plate in depressed relationship to the perforated plate including a lever carried by one of said handles.

7. In a capsule filling apparatus of the character described, a base plate, a perforated capsule positioning plate disposed over said base plate, a plurality of posts extending between the base plate and the perforated plate and connecting the same together into a unitary assembly and such that the perforated plate is disposed in spaced parallel relationship to the base plate, a middle plate disposed between said base and perforated plates and guided for up and down movement relative thereto, spring means yieldingly urging the middle plate upwardly and into sub-

stantial abutment with the perforated plate, at least one of said posts being provided with areas of reduced cross section forming one or more shoulders between the base and perforated plates, means carried by the middle plate and engageable with the reduced portions of said post to releasably hold the middle plate in spaced relationship to the top plate, and a lever carried by the middle plate for actuating said releasable holding means.
